CLAIM

We claim the ornamental design for a bottle, as shown and described.

DESCRIPTION

FIG. 1 is a perspective view of a bottle according to a first embodiment of the present design;

FIG. 2 is a left side elevational view of the bottle of FIG. 1, with the right side elevational view (not shown) being a mirror image thereof;

FIG. 3 is a front elevational view of the bottle of FIG. 1; FIG. 4 is a rear elevational view of the bottle of FIG. 1;

FIG. 5 is a top view of the bottle of FIG. 1;

FIG. 6 is a perspective view of a bottle according to a second embodiment of the present design;

FIG. 7 is a left side elevational view of the bottle of FIG. 6, with the right side elevational view (not shown) being a mirror image thereof;

FIG. 8 is a front elevational view of the bottle of FIG. 6; FIG. 9 is a rear elevational view of the bottle of FIG. 6; and, FIG. 10 is a top view of the bottle of FIG. 6.

The dash-dot-dash broken lines in the drawings showing the bottle depict the bounds of the claimed design. The evenly spaced broken lines in the drawings showing the bottle illustrate the portions of the bottle that form no part of the claim. Opposing detail lines seen through a transparent surface have been omitted in FIGS. 3-4 and 8-9 for ease of understanding.
